STRUCTURAL METAL AWNING

Lloyd H. Overly, Maryville, Tenn.

Application March 11, 1947, Serial No. 733,874

6 Claims. (Cl. 20—57.5)

1

This invention relates broadly to the art of structural metal awnings and in its more specific aspects it relates to structural metal awnings for installation on the exterior of buildings and the like, and is endowed with characteristics producing an awning of great flexibility in its application, and the nature and objects of this invention will be readily recognized and understood by those skilled in the arts to which it relates in the light of the following explanation and detailed description of the accompanying drawings illustrating what I at present believe to be the preferred embodiments and mechanical expressions of the invention from among various other forms, arrangements, combinations and constructions, of which the invention is capable within the spirit and scope thereof.

It is well known that metal awnings are endowed with many favorable characteristics which are not to be found in the usual awning having a metallic or wood framework between which fabric is stretched. It is obvious that such old type awnings quickly deteriorate, should be removed in winter, and flap and tear themselves to pieces when left in operative position during heavy winds.

These disadvantageous factors which I believe are to be found in practically every old type fabric awning are overcome in a structural metallic awning of the general character of my invention.

It has been found in metal awnings which are now known and which have been put to practical use, that certain characteristics thereof are undesirable. A metal awning of the character of my invention, while it may be dismantled and removed from installed operative position on a building or the like structure, is adapted and constructed for permanent installation in its operative building mounted position. It will be appreciated that a metal awning of this type is not adjustable to inoperative positions as in the old type fabric awning. In a shade producing installation including the old type folding or collapsible fabric awnings, it was merely necessary to adjust the awning to inoperative position when it was necessary to dispose a ladder or the like against the side of the building in order to wash windows above the awning or to paint the building above or to gain access for any purpose, to any portions of the wall above the awning. In view of the non-folding, non-collapsing structure of certain metal awnings, including that of this invention, it is highly desirable to provide some arrangement whereby access may be gained to points in the building wall above the level of the awning. The structural metal awning of this invention is so constructed that the above described access may be easily gained and it is therefore a purpose of this invention to provide

2

a structural metal awning of non-folding, non-collapsible type which permits easy access to areas of the building disposed above the awning.

It is also an object of this invention to provide a metal awning having one or more removable panels therein through which a ladder or the like may be projected for gaining access to the area above the awning.

I have also designed my awning structure so that the removable panels may be firmly disposed in operative awning associated positions and may be rapidly and easily displaced from association with the awning for the purposes above outlined.

A further characteristic of my structural metal awning resides in the provision of means for removably locking removable panels in operative association with the structure without requiring the use of screws, rivets, or the like securing means which would require considerable time and labor in unfastening in order to remove the panel.

Since awnings of this character are installed over building openings of various dimensions, it is necessary, in order to provide a useful and successful structure, to provide a fabrication of sufficient flexibility so that the basic structural characteristics thereof need not be changed to make the awning adaptable for each installation.

30 It is therefore a further object of this invention to provide an awning which may be made in various lengths and in which the number of removable panels may be varied without departing from the basic structural concept of the invention.

35 It is desirable and advantageous in a metal awning to provide means to prevent the formation of hot air pockets under the awning and it is therefore a feature of my invention to provide adjustable ventilating means in the awning.

40 Another characteristic of this invention resides in the feature of construction whereby a removable panel may with facility and without complete reconstruction be changed into an adjustable ventilator.

45 A further purpose of this invention is to provide a metallic awning structure which provides strength in the basic frame work and additional reinforcing means at the points of greatest stress.

Another feature and characteristic of my invention resides in the ease of the mounting means for the awning draperies.

50 A further object of my invention is to provide a structural metal awning which is relatively non-complex to fabricate and which is substantially rigid in its construction.

55 It is an object of one form of my invention to provide a metal awning of a sectional character which may be sold in knocked-down condition and easily assembled for installation on the job by unskilled workers.

It is a further object of this form of my invention to provide a sectional metal awning which is so constructed that sections thereof may be removed if desired while other sections thereof remain in installed position.

It is also an object of this invention to provide a metal awning so formed and constructed that metal having different finishes may be used for the different sections to provide a highly pleasing decorative effect.

In this form of my invention embodying a metal awning of a sectional nature, it has been my purpose to devise an awning which is inexpensive to produce and fabricate and may be easily installed.

With the foregoing general objects, features, and results in view, as well as certain others which will be apparent from the following explanation, the invention consists in certain novel features and designs, construction, mounting and combination of elements as will be more fully and particularly referred to and specified hereinafter.

Referring to the accompanying drawings:

Fig. 1 is a perspective view of an awning installation.

Fig. 2 is a view in end elevation with the end wall and end drapery removed.

Fig. 3 is a view taken on line 3—3 of Fig. 2 of the drawings.

Fig. 4 is a view in front elevation of an awning with parts thereof illustrated in section.

Fig. 5 is a front view in vertical section through the roof panels of the awning.

Fig. 6 is an end view in vertical section through a removable panel.

Fig. 7 is an end view in vertical section through a ventilating panel.

Fig. 8 is a perspective view of the panel fastening means, parts of the panel and awning structure being broken away.

Fig. 9 is a vertical sectional view showing a set of gutters with which the awning is provided.

Fig. 10 is a view taken on line 10—10 of Fig. 2 of the drawings.

Fig. 11 is a view in side elevation of a modified form of awning structure.

Fig. 12 is a view in front elevation of the modified form of awning illustrated in Fig. 11 of the drawings.

Fig. 13 is a view taken on the line 13—13 of Fig. 11 of the drawings.

Fig. 14 is a view taken on the line 14—14 of Fig. 12 of the drawings.

Fig. 15 is a view taken on the line 15—15 of Fig. 11 of the drawings.

Referring to the drawings wherein like characters of reference designate similar parts throughout the several views thereof, the structural metal awning of this invention may be fabricated of sheet metal and comprises what I shall term a basic supporting structure composed of a plurality of members so integrated that a substantially rigid structural frame work is produced, the frame work being adapted to mount and support various members, which when combined with the frame work provide a complete awning structure. I have so fabricated the various elements of the supporting structure that they may be associated together in forming a complete and operative structural metal awning with great facility.

The dimensions of the basic supporting structure may be varied within relatively wide limits to accommodate the awning to wall openings of various dimensions, for obviously the size of wall openings which are to be protected by the awning will differ in their dimensions. The awnings of

this invention may be fabricated in different sizes without varying the structural characteristics of the basic supporting structure.

The basic supporting structure or frame work includes a downwardly depending supporting flange 1 which is disposed for flat engagement against and fastening to the wall 3 of a building, the lower edge of flange 1 may be upwardly folded as at 6 to reinforce and strengthen the lower flange edge. At the upper edge, the flange 1 is folded over on itself to provide a further flange 7 of reduced width or depth relative to flange 1, the two flanges when in operative awning mounted positions lie in flat engagement. The flanges 1 and 7 are fastened to the wall by means of a plurality of screws, nails or the like 9. It will be evident from consideration of the drawings that the flanges 1 and 7 form a part of the basic supporting structure of the awning and provide the means for mounting the structure to a building wall, and that such flanges extend the width of the awning.

I provide a top cross rail 11, as a part of the basic supporting structure which rail depends downwardly at an oblique angle to flanges 1 and 7 with which it is integrally formed. The top cross rail provides the uppermost slanting surface of the awning proper. At the lower edge thereof the top cross rail is folded under to provide an upwardly inclined under flange 13.

Referring particularly to Fig. 10 of the drawings, it will be evident that the top rail 11 at each transverse end thereof is inwardly bent to provide an inwardly extending flange 15, the inner end of which is formed to provide an outwardly extending flange 17 whereby an inwardly directed pocket 19 and an outwardly directed pocket 21 is provided by the particular folding arrangement of the rail 11 at the ends thereof.

The basic supporting structure includes a bottom cross rail which is disposed in spaced relation to the top cross rail, and I have designated this bottom cross rail in its entirety by the numeral 23. The bottom cross rail as in the case of the top cross rail extends the full width of the awning and embodies a vertically disposed depending apron portion 25 and a top inclined portion 27 which forms a portion of the awning top surface. As in the case of the top cross rail, the bottom cross rail 23 is of the width of the awning structure. The transverse edges of the upper portion 27 of the lower cross rail are inwardly bent as at 29, to provide flanges forming a pocket for a purpose to be hereinafter described.

The vertical transverse edges of the apron portion 25, of cross rail 23, are inwardly folded as at 31 to provide a pocket for a purpose to be hereinafter described.

The apron 25 at its bottom edge is upwardly bent as at 33, the upper edge of which is folded to provide a downwardly extending pocket forming flange 35. It will be appreciated, particularly from consideration of Figs. 2 and 6 of the drawings, that the downward directed pocket is provided by and between flanges 33 and 35.

The top and bottom cross rails which have been hereinbefore described are rigidly associated in the awning structure by means of up and down or inclined end members and a plurality of intermediate connecting members, the number of such intermediate connecting members being dependent upon the width of the awning being fabricated. The connecting members are spaced apart one from the other and also from the end members.

The end rails 37 which are disposed between and rigidly connect the top and bottom cross rails, extend at substantially the same inclination as do the top and bottom rails. Each edge of each end rail 37 of an awning extends upwardly into the pocket 18 which is formed by the folds provided by the transverse edge of top rail 11. The end rails 37 may be secured at their upper ends to the top cross rail where they extend thereunder by means of riveting or in any other convenient and desirable manner. The lower ends of the end rails extend under the upper portion 27 of bottom cross rail 23, extending into the pocket 28 which is formed by the particular folding of the transverse edges of the upper portion 27 of the bottom cross rail. The bottom cross rail and the lower end of the end rails may be fastened together in any convenient manner such as by riveting. It will be evident that the end rails extend from substantially the apron 26 to the uppermost end of the top cross rail 11.

The outer longitudinal edge of each end rail between the top and bottom cross rails is inwardly bent as at 39 and is then outwardly bent as at 41 to provide an outwardly directed pocket particularly as shown in Fig. 3 of the drawings. A downwardly depending flange or wall 43 extends along the entire inner longitudinal edge of the end rails, the lower end of the flange 43 being horizontally disposed as at 45, the inner edge of the horizontal portion being upwardly bent and folded on itself to provide an upstanding lip 47. It will thus be seen that a gutter 48 is formed by the particular construction and configuration of the inner longitudinal edge of each end rail, and that the gutter extends the length of the end rails.

As I have hereinbefore stated, each metallic awning structure of the character of the one described in this application, comprises the end rails and one or more intermediate up and down or inclined rails which form a part of the supporting structure or frame work. In the drawings, I have designated such intermediate rails in their entirety by the numeral 49, such rails extending the full depth of the awning structure. Each of such intermediate rails includes a top plane portion 51, longitudinal flanges 53 depending from each longitudinal edge thereof, and upstanding lips 55 spaced inwardly from the flanges. It will be evident that longitudinally extending gutters 56 are provided along the opposite longitudinal edges of each intermediate rail 49. The intermediate rails at their upper and lower ends extend under the top and bottom cross rails 11 and 27 respectively to which they may be secured by riveting or in any desirable manner.

As disclosed particularly in Figs. 1, 4 and 5 of the drawings, a completed awning structure includes a pair of end rails and one or more intermediate rails, all of which are associated together to provide a substantially rigid metallic awning.

I provide upper and lower cross reinforcing members for additional bracing of the end rails and the intermediate rails. The upper reinforcing or brace rods 57 are provided in the following manner. Between the end rails and the next adjacent intermediate rail and between intermediate rails, the under flange 13 of top cross rail 11 is downwardly bent at substantially right angles to provide a flange 59 which extends substantially the entire width of the space between an end rail and an intermediate rail or between intermediate rails, the lower portion of said flange being cut out for the reception therethrough of

the gutters 48 and 56 which are formed on the longitudinal edges of the end and intermediate rails. Formed integrally with the lower end of each flange 59, I provide a portion extending forwardly at substantially right angles thereto, this portion 57 providing a cross brace which extends from and between the gutters of each end rail extending under and in contact with the gutters which are provided on all of the intermediate rails. The ends of brace 57 may be bent about gutters 48 as shown at 58 in Fig. 9. It will thus be seen that this particular bracing member 57 provides a further structural support for the end and intermediate rails.

A generally similar arrangement is provided for the lower ends of the intermediate and end rails. Between the end rails and the intermediate rails, and between intermediate rails, I provide a downwardly depending flange 61 integrally formed with the inclined portion 27 of lower cross rail 23, such flange 61 being provided with a forwardly extending brace member 63, which extends from and between the gutters on each end rail in contact with the gutters of all of the intermediate rails, for reinforcing thereof.

It will be appreciated from the above description that the basic supporting structure comprises spaced top and bottom cross rails connected by end rails and one or more intermediate rails or bars. I have devised novel and highly advantageous means for closing the openings which occur between either the end rails and intermediate rails, or between the intermediate rails. I utilize what I shall term roof panels which are formed of sheet metal and comprise a top flat portion 65 of substantially the same configuration as that defined by the opening between the intermediate and end rails, however, the roof panel top 65 is of greater length and width than is the opening which it is adapted to enclose so that it may rest upon the edges of the intermediate and end rails defining the opening or upon the edges of intermediate rails when the opening is so defined. The upper end of the roof panel when in operative position extends under the lower edge of the top cross rail, while the lower end of the roof panel rests upon the upper longitudinal surface of the portion 27 of lower cross rail 23.

Each roof panel element includes the upper top surface 65 and depending transverse and longitudinal integrally formed flanges 67 downwardly extending from the lower side of the top surface 65 and spaced inwardly a distance from the edges thereof. The downwardly depending flanges may be reinforced by an upwardly bent portion 69. The downwardly depending flanges 67 are inwardly spaced relative to the transverse and longitudinal edges of the top surfaces 65, a distance so that such flanges may snugly fit within the openings between end rails and intermediate rails or between intermediate rails, the flange 67 snugly bearing against the flanges 48 of the end rails and/or the flanges 53 of the intermediate rails.

Since the downwardly depending flanges 67 are integrally formed with the top 65 of each roof panel, a fold 71 results, providing a pocket 73 between the top 65 and the fold portion 71. The purpose of this pocket will become apparent as this description proceeds.

In order to removably mount the roof panels, in the openings between the rails and to guard against the undesired removal of these panels, I provide a plurality of locking members designated generally by the numeral 75 for locking

association between each roof panel and the gutters 48 and 56 of the end rails and intermediate rails respectively to which the roof panel is attached. The locking members comprise a soft metal cleat including a locking leg 77, which is centrally notched as at 79 and further includes an extended portion 81 integrally formed with said locking leg 77. The roof panels are preferably formed with the extending end portions 81 of the locking cleats fixedly disposed by welding or the like in the pockets 73 which are provided by fold 71 in the roof panels. It will be evident from consideration, particularly of Fig. 4 of the drawings, that the locking members 75 are fixed in spaced relation along the under side of the roof panel.

When a roof panel is disposed in position preparatory to being removably locked by means of the locking cleats 75, the depending notched locking legs 77 will extend from the roof panel below the gutters of supporting end or intermediate rails. In order to removably lock a roof panel in position, the mechanic catches hold of one end of the locking leg 77 with a pair of pliers and pulls thereon, which action pulls the roof panel tightly down into position whereupon the end of the tongue on the other side of the notch 77 is folded around under the gutter and then the end which was held by the pliers is wrapped about the gutter in the same manner, all to assume operative locking position as shown by dotted lines in Fig. 8.

In many instances where metal awnings of the type of this invention are mounted in operative position on the wall of a building it is necessary to gain access to the wall area above the awning, and this may be done by merely removing one or more of the roof panels, whereupon a ladder may be inserted through the opening between the end and intermediate rails. In order to remove a panel, it is merely necessary to grasp with a pair of pliers or the like, the ends of the locking leg of the cleat which are folded under and around the gutter and bend such leg into position so that the panel may be removed and the leg of the cleat will not catch upon the gutter. Of course, this operation must be done for each cleat which is employed in the locking of a roof panel. In the average installation, I have found that three cleats are generally sufficient for each side of a roof panel.

I have found that it is often desirable to provide some means for permitting hot air which may accumulate under the awnings, to escape therefrom. I have provided ventilating means which is simple to construct and easy to operate and does not substantially alter the basic awning structural features.

The ventilating means which I utilize consists of constructing one or any desired number of the roof panels in a particular installation with pivoting means at one end, so that the roof panel may be lifted and supported in such lifted position to thereby provide an opening through the top of the awning.

In Fig. 7 of the drawings, I have illustrated a ventilating roof panel and have shown in dotted lines such panel in lifted open ventilating position. A roof panel which is to function as a ventilator, is provided at its upper end with a transverse spindle 89 which extends through the downwardly depending flanges 67, of the roof panel and is pivotally supported in apertures which are provided in the downwardly depending flanges 53 of the adjacent gutters. As a supporting

means, I provide at the forward or lower end of the ventilating roof panel, a supporting bar 91, pivoted as at 93 to the underside of the top surface 65 of the roof panel, the forward edge of the supporting bar 91 being provided with a plurality of notches 95, therein for receiving the upper edge of the supporting cross braces 63. It will thus be evident that all that is necessary to raise and support in raised position a roof panel, is to take hold of the lower end of the supporting bar 91, swing the same upwardly so that the notched portion is clear of the cross brace 63, and then push upwardly to thereby open the panel to any desired position where it may be maintained by inserting the upper edge of the cross brace 63 in the adjacent notch.

At each end of the awning, I provide end panels 97, having at the rear vertical edge thereof, an inwardly directed flange 99, and at the upper inclined edge thereof an inwardly directed flange 101, which in operative position is disposed within the pocket formed by the flanges 39 and 41 of the end rails 37. The upper end or portion of the inclined flange 101 is disposed within the outwardly directed pocket 15, which is formed by the folding of the transverse edge of the top cross rail 11. The lower portion of the inclined flange 101, extends into the pocket 29 which is formed by the folding of the transverse edge of inclined portion 27 of the lower cross rail 23. The inclined edge 101 of the end panels is secured in position within the aforementioned folds of the various flanges described by riveting, screwing or in any other desired manner.

35 The front vertical edge of the end panel is provided with an inwardly directed flange 103, which is secured in any manner within the pocket provided by the folding of the flanges 39, which are provided at the vertical edges of the apron 25.

40 Along the lower edge of the end panels, I provide an upwardly extending flange or fold 105, formed with a downwardly depending flange 107 spaced therefrom providing a downwardly directed pocket extending the entire depth of the awning, that is, from the rear end to the forward end of each end panel.

The drapery which I shall designate in its entirety by the numeral 109, and which extends preferably across the front of the awning and along each side is preferably fabricated from one piece of sheet metal to provide an integral drapery unit. At the upper edge 110, the drapery is provided with a folded over portion 111, from the lower edge of which projects a substantially inwardly directed horizontal flange 113, and a fold over element 115. While I have disclosed in the drawings the drapery 109 as being formed integrally with the members 111, 113, and 115, it is to be understood that the drapery may with equal success, be a unit separate from the reinforcing member comprising the elements 111, 113, and 115.

In assembling the drapery to the awning structure, the upper portion thereof including the leg 111, is inserted in the pockets formed in the end panels by the folds 105 and 107, and the upper portions of the drapery and leg 111, which extend along the front of the awning are inserted in the pocket provided by the flanges 33 and 35, which are formed integral with and along the lower edges of the apron 25 of lower cross rail 23. The drapery 109 is secured in place within the pockets formed by the flanges of apron 25 and end panels 97 by riveting or by means of sheet metal screws 75 or in any other desirable manner. It will be evi-

dent that the flanges 113 and 115 will project inwardly and along with the leg 111, will provide a very satisfactory and strong reinforcing means for the lower part of the awning, these horizontal flanges 113 and 115 are cut at their corners in such manner that they may be fastened together by screws or the like 117, at the meeting corners thereof.

In Figs. 11 through 15 of the drawings, I have illustrated a modified form of my invention. In this type of metal awning, I have provided a structure composed of a plurality of panel sections spaced apart by intermediate panel sections, adjacent intermediate sections and panel sections being separably fastened together and each of such sections providing the roof portions and the front drapery portion of the awnings, and I also removably combine with the panel and intermediate rail sections, side or end draperies to complete the awning structure.

Each awning comprises a plurality of independent elongated panel sections generally designated by the numeral 119. Each of the panel sections 119 comprises a substantially vertically disposed supporting flange 121 which is adapted to be secured to a supporting wall 123 or the like. The panel sections 119 include an inclined roof forming or top portion 125 and a front drapery portion 127 which is downwardly inclined at an angle oblique to the angle of the roof or top portion. The longitudinal edges of the roof and drapery portion 125 and 127, respectively, are inwardly lapped as at 129, from the inner end of which lap or fold-over, I provide a downwardly depending flange 131.

The panel sections 119 are spaced apart and removably fastened to an adjacent intermediate panel section which I shall designate in its entirety by the numeral 133. Each intermediate panel section which is removably fastened to each adjacent panel section comprises a supporting flange 135 which is adapted to be fastened to the wall or other supporting structure 123 in any desirable manner, and each intermediate section also comprises a roof or top portion 137 which is downwardly inclined, and a drapery forming portion 139, which extends downwardly at an oblique angle to the roof portion. The longitudinal edges of the roof and drapery forming portions 137 and 139 respectively, of the intermediate panel section, are downwardly bent providing a flange 141, the lower end of which is formed to provide a horizontally extending portion 143, which in turn is upwardly bent at its inner edge to provide a flange 145, which structure produces a gutter 147. Thus, each intermediate panel section provides a gutter extending along and disposed below the longitudinal edges thereof.

In assembling the panel sections just described, an intermediate panel section 133 is fastened to the wall or the like structure by means of the supporting flange 121. This first installed intermediate section provides the end intermediate section and therefore is disposed on the wall a distance, from the position one end of the awning will take, equal to the width of a panel section 119. Any panel section 119 is then used to form the awning end and is disposed with the depending flange 131 thereof in position abutting the depending flange 141 of the intermediate section, whereupon this awning end forming panel section is secured to the wall or like structure by nailing or otherwise fastening the supporting flange 121 thereto. It will be evident that the

lap or fold-over 129 will lap over and rest upon the intermediate panel section 133.

With a panel section and an end section in the positions described, they are removably fastened together by screws and nuts 149 or in any other convenient manner. In order to reinforce and strengthen the structure, I may employ gusset plates or the like 151 which are fastened to the depending flange 141 and extend between such flange of the roof section 137 and the drapery section 139 to reinforce them at the angle therebetween. A panel section is then installed in like manner on the other side or edge of the intermediate section and fastened thereto, then an intermediate section is installed, and so on, depending upon the width of the awning.

It will be appreciated from the above description of the method of installing the sectional awning of this form of my invention that panel sections 119 are always used as the end sections or members of a completed awning and that the entire awning roof and front panel drapery structure is composed of a series of alternately positioned panel and intermediate sections, all being separably fastened together in the manner described. It will also be clear that the number of panel and intermediate sections which compose an awning is dependent upon the desired width of the completed awning structure.

When the roof and front drapery forming panel and intermediate sections have all been installed, each end forming panel section 119, will provide at the awning ends downwardly depending flanges 131. These end flanges provide the supporting means for the awning end or side draperies which are about to be described.

The side or end draperies are structurally generally similar to the panel sections which form the roof and front draperies, and are of sectional structure so that the awning end draperies are composed of a plurality of independent vertically disposed separably associated end drapery sections.

The end drapery structure of my awning comprises an inner major drapery supporting section 153 which is adapted to provide the end drapery section which is disposed against and fastened to the wall or supporting structure 123 by means of screws, nails, rivets or the like 155, which extend through an inwardly directed flange 157 of the inner major supporting section 153, for fastening into the wall 123. This flange 157 is bent and extends from one longitudinal edge of this section 153. The other or opposite longitudinal edge of section 153 is provided with an inwardly directed flange 159 and a fold-over 161 which provides an outwardly directed pocket formed by the flange 159 and the fold-over 161. The top transverse edge of end section 153 is obliquely cut so that when the section is positioned with the flange 157 against the wall, the inclined top will mate with the inclination of the roof portion of panel section 119, the end section 153 being vertically disposed. The top of the section 153 lies flat against the depending flange 131 of panel section 119, and is separably fastened thereto by means of screws and nuts or the like 163.

The end drapery structures for each end of the awning are composed of the end drapery major supporting sections 153 and alternately disposed panels 165 and 167, the panel 165 having the longitudinal edges lapped as at 169, which laps are formed with inwardly directed flanges 171. One flange 171 on the panel installed adjacent to

the end major supporting panel 153 is received in the pocket provided by flanges 159 and 161 and is removably fastened therein by means of screws and nuts or the like 173, while the flange 171 along the opposite edge of section 165 is received in the pocket formed by spaced flanges 169 and 161 which are provided on panel section 167. It will be evident that the outermost end drapery forming section has its forward and upper edges cut to conform to the outline of the roof portion and front drapery portions of panel section 119. All of the sections 153, 165, and 167, are removably fastened to the depending flange 171 by means of the screws and nuts or the like 163.

Thus, each end drapery structure is composed of an independent end member 153 and a series of independent alternately spaced end sections 165 and intermediate end sections 167, the latter providing at their longitudinal edges, pockets for receiving the inwardly directed flanges of the end sections 165.

An awning of sectional construction such as that illustrated in Figs. 11 to 15 of the drawings may provide a highly decorative effect without requiring the application of any finishing paint or the like thereto. The various sections from which the awning is composed may be furnished in metals having different finishes so as to provide a striped effect. Or this striped effect may be achieved by painting the panels various colors. It will also be understood, that the awnings may be sold in knocked-down condition, that is the various panel sections may be separately manufactured and sold and shipped to the job and then installed and combined to produce a complete awning structure.

I claim:

1. In a structural metal awning, a basic supporting structure adapted to be mounted on the wall of a building, said structure including a plurality of members, certain of said members spaced apart providing openings therebetween, roof panels mounted on and supported by said members for closing the openings, and flexible means fixedly attached to said roof panels and extending therefrom, the extending section of said means having independently movable portions, and substantially rigid means depending from certain of said members of the structure, the independently movable portions of said flexible means being manipulable for releasable locking association with said substantially rigid means, for removably locking said panels on the members of said structure.

2. In a structural metal awning, a basic supporting structure adapted to be mounted on the wall of a building, said structure including a plurality of members, certain of said members spaced apart providing openings therebetween, roof panels mounted on and supported by said members for closing the openings, flexible locking means fixedly attached to said roof panels and extending therefrom, and rigid means depending from certain of the members of said structure, the flexible locking means being manipulable for releasable locking association with said rigid means for removably locking said panels on the members of said structure, said rigid means providing a gutter disposed below the roof panels and the members of said structure to catch leakage occurring therebetween.

3. In a structural metal awning, a basic sup-

porting structure adapted to be mounted on the wall of a building, said structure including spaced up and down rails having gutters depending from at least one longitudinal edge thereof and disposed below the rails in position to catch drippings from the rail edges, and spaced top and bottom cross rails fastened to the ends of said up and down rails, and removable panels mounted between and supported by the spaced up and down rails and the spaced cross rails, said panels having depending flanges extending into the gutters when the panels are in position on the structure.

4. In a structural metal awning, a basic supporting structure adapted to be mounted on the wall of a building, said structure including spaced up and down rails having gutters depending from at least one longitudinal edge thereof and disposed below the rails in position to catch drippings from the rail edges, and removable panels mounted between and supported by the spaced up and down rails, said panels having depending flanges extending into the gutters when the panels are in position on the structure, and means for supporting said up and down rails.

5. In a structural metal awning, a basic supporting structure adapted to be mounted on the wall of a building, said structure including end rails having gutters depending from the longitudinal inner edges thereof in position to catch drippings from the rails, and top and bottom rails fastened to the ends of said end rails, and an intermediate rail fastened at the ends thereof to said top and bottom rails and spaced from said end rails, said intermediate rail having gutters formed along and below the longitudinal edges thereof, in position to catch drippings from the rail, and a removable panel mounted between and supported by the spaced end and intermediate rails and said top and bottom rails, said panel having depending flanges extending into the gutters when the panel is in position on the structure.

6. In a structural metal awning, a basic supporting structure adapted to be mounted on a wall of a building, said structure including spaced up and down rails having gutters depending from at least one longitudinal edge thereof and disposed below the rails in position to catch drippings from the rail edges, and spaced top and bottom cross rails fastened to the ends of said up and down rails, and removable panels mounted between and supported by the spaced up and down rails and the spaced cross rails, and said bottom cross rail including an apron portion, the apron portion having a pocket formed therein for receiving a drapery.

LLOYD H. OVERLY.
